United States Patent Office

Des. 195,665

Patented July 16, 1963

195,665

CLIP NECKTIE

Warren W. Welch, 1224 E. Monument St.,
Colorado Springs, Colo.

Filed Sept. 4, 1962, Ser. No. 71,555

Term of patent 14 years

(Cl. D3—16)

FIG.2

FIG.1

FIG. 1 is a front view of the clip necktie, showing my new design.

FIG. 2 is a top plan view of FIG. 1.

The essential features of my design reside in the full line disclosure on the drawings.

I claim:

The ornamental design for a clip necktie, as shown and described.
